Inventor
William H. Pavitt, Jr.
John E. Hubbell

UNITED STATES PATENT OFFICE.

WILLIAM H. PAVITT, JR., OF BROOKLYN, NEW YORK.

CONCRETE FOUNDATION AND METHOD OF MAKING SAME.

1,384,402.

Specification of Letters Patent. Patented July 12, 1921.

Application filed November 15, 1919. Serial No. 338,374.

To all whom it may concern:

Be it known that I, WILLIAM H. PAVITT, Jr., a citizen of the United States, and resident of Brooklyn, in the county of Kings and State of New York, have invented certain new and useful Improvements in Concrete Foundations and Methods of Making Same, of which the following is a specification.

10 My present invention comprises improvements in the form of and method of constructing concrete foundations for coke ovens and for other apparatus and structures where relatively large foundations carrying heavy loads are required; and the general object of the invention is to provide for the construction of a foundation of this character which shall possess ample strength on the one hand, and on the other hand is 15 relatively easy and inexpensive to construct.

The various features of novelty which characterize my invention are set forth in the claims annexed to and forming a part of this specification. For a better understanding of the invention however, reference should be had to the accompanying drawings and descriptive matter in which I have illustrated and described a preferred construction and method of making the same.

30 Of the drawings:

Figure 1 is a plan of a partially completed foundation; and

Fig. 2 is a section on the broken line 2-2 of Fig. 1.

35 The foundation shown as partially constructed in the drawings, comprises a base or bed layer of concrete A, concrete columns or posts B rising from the base A, a cap layer C of concrete carried by the columns B, and earth filling D filling the space surrounding the columns B and extending between the base and the cap layer C.

40 Advantageously the layers A and C are connected at their edges as shown in the drawings, by a vertical concrete wall E.

In constructing the foundation described, the first step will ordinarily be to excavate the earth on the foundation site to a sufficient depth to reach a sub-soil stratum of 45 sufficient bearing strength to support the foundation and its load. The next step is to form the foundation layer A of concrete. This may be done in the usual manner. Preferably short, vertical reinforcing bars

50 G are put in place in the layer A at the points where the columns B are to be sub-

sequently erected. After the layer A is in place, the columns B and the wall E are formed. The columns B are preferably cylindrical, and the ease and relative inexpensiveness with which these may be formed in practice, and the simple and effective character of the molds in which they are formed, constitute important characteristics of the invention. Preferably, reinforcing 60 bars H are inserted in the upper ends of the columns B as shown. After the columns B and the wall E are formed, the space surrounding the columns is filled with earth D to the level of the under side of the cap 70 layer C and the latter is then formed. The earth filling D, which should be sufficiently compacted for the purpose, supports the material forming the layer A while the latter is plastic and is not supported by the 75 wall E and columns B.

It will be understood, of course, that in the finished foundation, the parts B and the wall D are integrally connected to the base and to the cap layers A and C. 80

In practice the foundations may well be formed in successive horizontal sections, so that the earth E, as excavated to provide the site for a section of the base layer A, may be thrown back between the columns B 85 formed on a previously built section of the base layer A. This makes unnecessary more than one handling of much of the earth which must be excavated. In practice also, the tops of the columns B as formed will 90 be a few inches above the bottom level of the cap layer C.

The foundation formed in the manner described, is simple and strong. While the earth filling D cannot be relied on to carry 95 any portion of the vertical load on the cap layer C, it gives lateral stability to the columns B and thereby materially strengthens the structure against any tendency to fail by a horizontal movement of the cap 100 layer C relative to the base layer A.

The foundation and method of constructing it disclosed herein is of especial value, because of the relatively low construction cost, where the excavation necessary to secure a proper ground support for the base layer A is relatively small and where the yard level or other requirements make necessary a substantial distance between the top and bottom of the foundation. 105

In such cases a foundation may be constructed in accordance with the present in-

vention for a substantially lower cost than can a foundation for the same purpose made by driving piles and capping the piles or made of a solid mass of concrete.

5 For example, a single coke oven battery foundation of the not unusual dimensions of forty feet in width and one-hundred-seventy-five feet in length, constructed in accordance with the present invention, with
10 columns B, eight feet high, would require approximately eighteen hundred cubic yards of concrete less than would be required in a solid concrete foundation of the same over all dimensions. The load on the earth beneath the foundation would be about four hundred pounds per square foot less with
15 my new foundation than with the solid foundation in the example given above, since the earth filling D is of a specific
20 gravity substantially less than that of concrete.

While in accordance with the provisions of the statutes I have illustrated and described the best form of my invention now known to me, it will be apparent to those skilled in the art that changes may be made
25 in the form of the apparatus and of the

mode of constructing it disclosed, without departing from the spirit of my invention as set forth in the appended claims.

Having now described my invention, what I claim as new and desire to secure by Letters Patent is:

1. The method of forming an extended concrete foundation which consists in forming a concrete base layer, erecting spaced apart concrete posts on said layer, filling the space surrounding said posts with earth, and forming a cap layer of concrete on said posts and the earth filling about them.

2. A concrete foundation comprising a concrete base layer, spaced apart concrete posts rising from, an integrally connected to said base layer, a cap layer of concrete mounted on, and integrally connected to said posts, and a filling of earth about said posts adapted to serve as a support for the portions of the cap layer between the posts in forming the cap layer, and to give lateral stability to said posts.

Signed at New York, in the county of New York and State of New York, this twelfth day of November, A. D. 1919.

WILLIAM H. PAVITT, JR.
